UNITED STATES PATENT OFFICE.

JOHN QUIST, OF MYSTIC, IOWA, ASSIGNOR OF ONE-HALF TO CHARLES L. BERRY, OF WINTERSSET, IOWA.

COMBINED PIPE AND NUT WRENCH.

Application filed October 5, 1922. Serial No. 592,567.

To all whom it may concern:

Be it known that I, JOHN QUIST, a citizen of the United States, residing at Mystic, in the county of Appanoose and State of Iowa, 5 have invented certain new and useful Improvements in Combined Pipe and Nut Wrenches; and I do declare the following to be a full, clear, and exact description of the invention, such as will enable others 10 skilled in the art to which it appertains to make and use the same.

My invention relates to improvements in wrenches and more particularly to those of the type in which the movable jaw is forced 15 tightly toward the fixed jaw under the influence of the handle, when the wrench is in use, the object being to provide an extremely simple and inexpensive, yet a highly efficient and reliable wrench of this character.

20 With the foregoing in view, the invention resides in the novel subject matter herein-after described and claimed, the description being supplemented by the accompanying drawing.

25 Figure 1 is a perspective view of a wrench constructed in accordance with my invention,

Fig. 2 is a longitudinal sectional view through the front end portion of the wrench, 30 Figs. 3 and 4 are perspective views showing the fixed jaw body and the movable jaw respectively,

Fig. 5 is a perspective view of the operating dog for the movable jaw, and

35 Fig. 6 is a perspective view of the bifurcated front end of the handle.

In the drawing above briefly described, the 40 numeral 1 designates an elongated fixed jaw body having a forwardly extending fixed jaw 2 at one end and a rearwardly extending lug 3 at its other end, said lug being preferably of less width than the body while the latter and the jaw 2 may well be of uniform width. A guide opening 4 is formed in the body 1 from end to end and opens also through the 45 rear side of the body as indicated at 5 and through the front side thereof as shown at 6. This guide opening slidably receives the shank 7 of a movable jaw 8 which is parallel with the jaw 2. The rear edge of the shank 7 is provided with suitable teeth 9 engaged by a dog 10 whose front end is received within the portion 5 of the guide opening.

The numeral 11 designates a suitable elongated handle having a bifurcated front end

whose furcations straddle the lug 3 and are pivoted thereto as indicated at 12. The rear end of the dog 10 is received also in the bifurcated front end of the handle 11 and is pivoted thereto as shown at 13. This dog is provided, immediately behind the body 1, with a transverse head 14 which is preferably of cylindrical form with concave ends 15 which may readily be gripped between the thumb and forefinger for the purpose of releasing the dog when it is desired to increase the distance between the jaws 2 and 8. If desired, the head 14 may have a longitudinal bore 16 therethrough and the numeral 17 designates a recess in the rear side 70 of said head. This recess receives the reduced front end 18 of a flat spring 19 whose rear end is secured by a screw or the like 20 in a shallow recess 21 formed in the back edge of the handle 11. This spring normally holds the dog in engagement with the teeth 9 but permits retraction of said dog whenever necessary.

The shape of the teeth 9 is such that it is 80 simply necessary to press the jaw 8 towards the jaw 2 in order to properly engage both jaws with the pipe, nut, or other object to be turned, whereupon the dog will click over the teeth until the proper adjustment has been made. Then by forcing the handle 85 in the proper direction, the oblique dog 10 thrusts upon the shank 7 of the jaw 8 in such a manner as to cause this jaw to tightly grip the work. It will be seen that the gripping action increases with the amount of 90 force applied to the handle and hence that there is no danger of the jaws slipping.

If desired, the sides of the body may be 95 formed with openings 22 through which the front end of the dog 10 and the teeth 9 may be viewed, so that it may readily be seen when they are properly engaged with each other.

As excellent results have been obtained 100 from the details disclosed, they are preferably followed, but within the scope of the invention as claimed, numerous minor changes may of course be made.

I claim:

1. A wrench comprising a fixed jaw body 105 having a forwardly extending work-engaging jaw at one end and a rearwardly extending lug at its other end, said body having a guide opening from end to end which opens also through the front and rear 110

edges of said body, a movable jaw having a shank slideable in said guide opening and provided with teeth on its rear edge, a handle pivoted at its front end to said rearwardly extending lug, and a dog having its rear end pivoted to said handle at a point spaced laterally from the handle pivot, said dog extending obliquely to the shank and engaging the teeth thereof.

10 2. A wrench comprising a fixed jaw body having a forwardly extending work-engaging jaw at one end and a rearwardly extending lug at its other end, said body having a guide opening from end to end which

opens also through the front and rear edges of said body, a movable jaw having a shank slideable in said guide opening and provided with teeth on its rear edge, a handle having a bifurcated front end straddling and pivoted to said rearwardly extending lug, and a dog having its rear end pivoted between the handle furcations, said dog extending obliquely to the shank through the opening at the rear side of the body and engaging the teeth of said shank.

In testimony whereof I have hereunto affixed my signature.

JOHN QUIST.
